[57] CLAIM

The ornamental design for a motor car body, as shown and described.

DESCRIPTION

FIG. 1 is a perspective rear view of a motor car body showing my design;

FIG. 2 is a perspective front view thereof;

FIG. 3 is a left elevational view thereof;

FIG. 4 is a right elevational view thereof;

FIG. 5 is a front elevational view thereof; and,

FIG. 6 is a rear elevational view thereof.

The broken lines shown in all drawing views are for illustrative purposes only and form no part of the claimed design.
